US00D602493S

(12) **United States Design Patent**
Beale

(10) **Patent No.:** **US D602,493 S**
(45) **Date of Patent:** **** Oct. 20, 2009**

(54) **INPUT DEVICE**

(76) Inventor: **Theodore Beale**, 86 Baarerstrasse, Zug (CH) 6300

(**) Term: **14 Years**

(21) Appl. No.: **29/304,106**

(22) Filed: **Feb. 25, 2008**

(51) LOC (9) Cl. **14-02**

(52) U.S. Cl. **D14/455; D14/406**

(58) **Field of Classification Search** **D14/454, D14/455, 456, 320, 331, 333, 334, 335, 338, D14/339, 340, 341, 342, 345, 346, 347, 387, D14/390, 391, 392, 393, 394, 395, 396, 397, D14/398, 150, 247, 248, 900, 901, 902, 402, D14/406, 426, 432, 439, 453, 457, 137, 138, D14/218, 315, 327; D13/168; D18/12.2, D18/7, 52, 24, 25, 29, 1, 2; 235/145 R; 341/22, 341/27, 28; 345/168, 169, 170, 171, 172, 345/947, 948, 163; 379/368, 915, 433.07, 379/433.06; 400/109, 110, 111, 472, 484, 400/485, 486, 487, 490, 491, 492, 494; 455/550.1, 455/556.2, 186.2, 575.1**

CLAIM

The ornamental design for an input device, substantially as shown and described.

DESCRIPTION

FIG. 1 is a right-front perspective view of one embodiment of an input device showing the design;

FIG. 2 is a left-front perspective view thereof;

FIG. 3 is a top view thereof;

FIG. 4 is a front view thereof;

FIG. 5 is a left side view thereof; and,

FIG. 6 is a right side view thereof.

The portions shown in broken lines are for illustrative purposes only and form no part of the claimed design.
